(57) **CLAIM**

The ornamental design for a gas injector for metal powder manufacturing equipment, as shown and described.

DESCRIPTION

FIG. 1 is a perspective view of a gas injector for metal powder manufacturing equipment showing our new design; FIG. 2 is a front view thereof;

FIG. 3 is a top plan view thereof;

FIG. 4 is a bottom plan view thereof;

FIG. 5 is a cross-sectional view taken along line 5-5 in FIG. 2; and,

FIG. 6 is a cross-sectional view taken along line 6-6 in FIG. 3.

The evenly-spaced broken lines illustrate portions of the gas injector for metal powder manufacturing equipment that form no part of the claimed design. The dash-dotted broken lines denote the boundary of the claim and form no part of the claimed design.
